UNITED STATES PATENT OFFICE

FORTUNATO BRANICA, OF BROOKLYN, NEW YORK

COIN CONTROLLED VENDING APPARATUS

Application filed June 3, 1931. Serial No. 541,810.

This invention relates to vending apparatus wherein the operation of means to deliver merchandise from the apparatus is controlled by the depositing of a coin in a coin chute, and it is the primary object of the invention to provide an improved vending apparatus of this character which is novel and cheap in structure.

It is a further object of the invention to provide apparatus of this character wherein the merchandise delivery means is in simulation of a dredging machine arranged in a casing having a transparent wall portion whereby the operation of the delivery means and the delivery of the merchandise may be observed.

Another object of the invention relates to improved means for actuating the delivery means including a rotatable actuating shaft normally uncoupled from the delivery means and adapted to be coupled therewith by the depositing of a coin in a coin chute, and to improved means for maintaining the operative connection between said shaft and the delivery means and the breaking of said connection upon a predetermined number of revolutions of the shaft.

A further object of the invention is the provision of means for normally uncoupling the actuating shaft from the delivery means and adapted to couple said shaft with the delivery means by means coupled with and actuated by the shaft by a coin upon a coin seat in a coin chute, and said latter means adapted to actuate mechanism to effect coupling of the actuating shaft with the delivery means, and means operative upon a complete cycle of operations of the delivery means to uncouple the shaft from the delivery means.

Another object of the invention relates to the provision of an auxiliary support for a coin deposited in the coin chute during the operation of the delivery means and adapted to be actuated from the delivery means to release and permit the coin supported thereby to drop to the coin seat in position for coupling of the actuating shaft with the means to effect operation of the means to couple the shaft with the delivery means.

Other objects and advantages will hereinafter appear.

In the drawings accompanying and forming a part of this application, Figure 1 is a longitudinal sectional view of a vending apparatus illustrating an embodiment of my invention, the section being taken on the line 1—1 of Figure 2 looking in the direction of the arrows.

Figure 2 is a front elevation. 60

Figure 3 is a view looking at the top of the casing.

Figure 4 is a cross sectional view taken on the line 4—4 of Figure 2 looking in the direction of the arrows. 65

Figure 5 is a detail view of means associated with the delivery means for effecting uncoupling of said means from its actuating shaft.

Figure 6 is a view taken on the line 6—6 of Figure 5 looking in the direction of the arrows, and showing the means for uncoupling the actuating shaft from the delivery means. 70

Figure 7 is a detail view, in front elevation and partly in section, of the actuating shaft 75 showing the operating means between said shaft and the delivery means and the means associated with the delivery means for uncoupling the shaft therefrom.

Figure 8 is a longitudinal sectional view 80 of the coin chute and having associated therewith coin controlled means for effecting actuation of the means to couple the actuating shaft with the delivery means, the section being taken on the line 8—8 of Figure 9 looking in the direction of the arrows. 85

Figure 9 is a front elevation of the means for coupling the actuating shaft with the delivery means and the coin controlled means in relation to the chute for effecting actuation of the means to couple the shaft with the delivery means. 90

Figure 10 is a perspective view of the mechanism shown in Figure 9. 95

Figure 11 is a perspective view of the mounting means for the mechanism shown in Figures 9 and 10.

Figures 12 and 13 are perspective views of parts of the coin controlled means for 100

effecting coupling of the actuating shaft with the delivery means; and

Figure 14 is a detail sectional view of the casing to show the arrangement of a merchandise compartment therein with delivery outlet means leading therefrom and a compartment in communication with and for supplying merchandise to the first compartment.

In carrying out the embodiment of the invention illustrated there is provided a casing or cabinet substantially of rectangular shape provided with a merchandise supply compartment A and a merchandise delivery compartment B, the compartment A being formed by a partition 15 extending between the sides and from the top to adjacent the bottom of the casing and having the bottom 16 arranged in an arc of a circle with the ends terminating at the sides of the casing, as at 17 in Figures 1 and 2, and extended forward of the partition 15 to constitute the bottom of the compartment B, said latter compartment being formed by the partition 15 and a plate 18, preferably of transparent material. The compartment A is connected with the compartment B through an arched opening 19 (Figure 2) whereby the merchandise, in the present instance candy, moves by gravity through said opening from the compartment A to the compartment B due to the circular arrangement of the bottom. The merchandise is delivered from the compartment B through outlet means in the form of a chute 20 having a hopper inlet 21 centrally of and above the merchandise level in said compartment, the chute 20 being directed laterally of the hopper inlet and leading to a bottom 22 of a compartment C inclining downward from the rear to the front and bottom of the casing adjacent to an inlet 23 to said compartment and through which the delivered merchandise is received, the top of said compartment being closed by the bottom 16 for compartments A, B and a plate 24 extending between the casing sides and the front wall 18 of compartment B and front wall of the casing, said plate also serving as the support upon which the delivery mechanism is mounted. The front wall of the casing has a circular opening therein closed by a plate of transparent material, such as glass, as shown at 25, through which to observe the operation of the delivery means, the lower portion of said plate being rendered opaque, as by painting or otherwise, as shown at 26 in Figure 2, to obscure from view the plate 24 and the mounting means for the delivery mechanism.

The merchandise delivery or dispensing mechanism is constructed to simulate a dredging machine and comprises a scoop in the form of a cup member 28 secured at the bottom to one arm of an angle member 29 secured by the other arm in a block 30 mounted intermediate the ends upon the end of a shaft

31 and serving as a counterweight for the scoop. The shaft is rotatably supported in legs 32 of a U-shape bracket secured upon a plate 33 (Figure 11) secured upon the plate 24. A worm wheel 34 fixed on said shaft meshes with a worm 35 on a shaft 36, herein termed as the actuating shaft, mounted to rotate on an axis transverse to the shaft 31 in brackets 37 fixed upon and extending upward from the plate 33. The worm 35 is loose on the shaft and has diametrically opposite recesses in one end to arrange the same as a clutch member, and is connected with the shaft to rotate therewith by a clutch member 38 in the form of a sleeve slidably mounted on the shaft 36 juxtaposed to the worm and adapted to rotate with the shaft by a pin fixed in and the opposite ends extending from the shaft engaging diametrically opposite slots in the sleeve, as at 39 in Figure 7. The end of the sleeve opposite the worm is provided with diametrically opposite projections to serve as clutching jaws adapted to engage the worm recesses to couple the worm through the sleeve to the shaft, the sleeve being urged toward the worm by a spring 40 coiled about the shaft and confined between the sleeve and a collar 41 fixed on the shaft.

The shaft 36 is extended to adjacent a side wall of the casing and has a bearing support in a sleeve hub 42 of a crank 43 rotatably mounted in a bearing member in the casing wall, as at 44. The crank is adapted to be connected with and rotate the shaft when rotated in one direction, in the present instance in clockwise direction, and to be disconnected from and be rotated free of the shaft when rotated in the opposite direction. For this purpose the inner end of the crank sleeve is arranged with clutch jaws and a clutch member, in the form of a sleeve 45 is mounted on the shaft juxtaposed to the crank sleeve and having jaws at one end to co-operate with the clutch jaws of the crank sleeve, said clutch sleeve being mounted on the shaft to, have sliding movement and rotate therewith by a pin fixed in the shaft with the ends extended from opposite sides engaging slots in the sleeve, as at 46, and urged toward the crank sleeve and clutching position by a spring 47 coiled about the shaft and confined between the clutch member and a collar secured on the shaft, as shown in Figure 7. To hold the shaft against rotation in anti-clockwise direction and permit of rotation of the shaft in clockwise direction a yielding detent or pawl 48 co-operates with a ratchet wheel 49 fixed to the shaft 36.

The ratio of the worm gearing is such as to impart one revolution to the scoop carrying shaft 31 and revolve the scoop 28 through a complete circle by a predetermined number of revolutions of the actuating shaft 36, the scoop during this movement being dipped into the compartment B to be filled with the

merchandise and during its travel above the shaft 31 delivering the merchandise into the hopper inlet of the delivery chute 20. To bring the scoop to rest after the delivery of the merchandise therefrom means are provided to automatically actuate the clutch member 38 to unclutching position and thereby release the scoop from the actuating shaft 36 and releasably retain the clutch member 66 on the actuating shaft as it is rotated passing through a slot 66' in the wall of the chute 54 and engaging the coin on the coin seat, the continued rotation of the shaft impinging the finger and coin against the plate 64 coupling the plate to the shaft and moving it to the dotted line position shown in Figure 8. This movement of the plate effects further releasing movement of the clutch member 38 and permitting the shifter finger 50 to be moved out of engagement with the clutch flange 38' by its spring 52, and the clutch to be moved into clutching relation with the worm 35 by the spring 40. This means comprises an arm 67 pivotally supported at one end by a bracket 68 mounted on the plate 33 to extend upwardly from said plate and have movement in the plane of the actuating shaft, the arm being of arcuate shape in longitudinal section and engaging the clutch flange 38', as shown in Figure 9. A lever 69 is pivotally supported intermediate its end in the bifurcation of a post 70 fixed to and extended upward from the plate 33, the one end of the lever, as at 71, being reduced in thickness and engaging in a bifurcation 67' in the free end of the arm 67, the shoulders at opposite sides of and formed by the reduced portion being arranged as cam faces to engage the arm 67 at opposite sides of the bifurcation. As the plate 64 is actuated and moved to the dotted line position by the finger 66 on the actuating shaft by the interposing of a coin between said finger and the plate an arm 72 fixed to the plate carrying shaft 65 extended forwardly therefrom at a right angle to the plate and over the end of the lever 69 opposite to its connection with the arm 67 is moved from the full line position to the dotted line position shown in Figure 8, thereby rocking the lever and effecting movement of the arm 67 to move the clutch flange 38' out of engagement with and releasing the shifter finger 50, said finger moving from the dotted line position to the full line position shown in Figure 9. As soon as the shifter finger is released from the clutch flange the tension of the clutch actuating spring 40 acting through the clutch member on the arm 67 will move the lever 69 to the full line position shown in Figure 8 and the coin arresting plate 64 relative to the coin seat 63. By the continued rotation of the actuating shaft 36 the finger 66 will ride off from the coin impinged against the plate 64 releasing the coin, which will drop into a compartment D in the bottom of the casing formed by the bottom of the partitions A, B and the supporting plate 24 and a transverse partition extending transversely from the front to the rear of the casing, as indicated by dotted lines 73 in Figures 2 and 4.

To prevent a coin inserted in the coin chute from passing through the coin chute when the coin arresting plate 64 is in the dotted line

position shown in Figure 8 and during the delivery movement of the scoop, the plate 59 is moved from the full line position to the dotted line position shown in Figure 8 through the action of the spring 61, said plate in normal position with the parts idle being moved to and retained in the full line position by a rod 74 secured at one end in the extended end of the plate carrying shaft 60 and extending downward therefrom adjacent to the scoop carrying shaft 31 and shaped at said end to constitute a cam engaging an abutment 75 carried by and extended laterally from a collar 76 secured on said shaft. As the shaft 31 is rotated the abutment is moved out of engagement with the cam portion of and releases said rod permitting the spring 61 to move the plate to the dotted line position. As the shaft approaches the termination of its revolution or merchandise delivery movement the abutment engages with the cam portion of the rod rocking the shaft 60 and thereby the plate 59 away from the chute wall releasing a coin supported thereby and permitting it to drop relative to the coin seat 63 and the plate 64, which plate has been returned to its normal full line position shown in Figure 8 through the movement of the clutch to clutching position acting through the arm 67 on the lever 69.

For the purpose of getting access to the casing the rear wall 77 is hingedly mounted, as at 78, and is provided with a hasp 79 of angle form having a perforation for the passage of a staple 80 for the engagement of the shackle of a padlock 81. To supply merchandise to the compartment A there is provided an opening in the top of the casing having a hingedly supported closure 82 secured in closed position by a pair of hasps 83 extending transversely of the closure from substantially midway to opposite sides thereof and to beyond the sides and having perforations for the passage of staples for the engagement of the shackle of padlocks 84.

It will be obvious that various modifications may be made in the construction and arrangement of parts, and that portions of the invention may be used without others, and come within the scope of the invention.

Having thus described my invention, I claim:

1. In coin controlled vending apparatus, a rotatable actuating shaft, merchandise dispensing means including a rotatable shaft, a member loose on the actuating shaft having a driving connection with the shaft of the dispensing means and arranged as a clutch member, a clutch member rotatable with and slideable on the actuating shaft normally urged to clutching position, a clutch shifter rotatable with and operative upon each revolution of the shaft of the dispensing means to move the clutch member on the actuating shaft to and releasably retain it in un-

clutching position, and means normally uncoupled from and adapted to be coupled with the actuating shaft by a coin and rotation of said shaft to release the shifter from the clutch member and permit the clutch member to move to clutching position and connect the actuating shaft with and actuate the shaft of the dispensing means.

2. In coin controlled vending apparatus, a rotatable actuating shaft, a second rotatable shaft, merchandise dispensing means carried by said latter shaft and moved through a circular path by the rotation of the shaft, a worm wheel on said second shaft, a worm loose on the actuating shaft meshing with the worm wheel, means on the actuating shaft to couple the worm with the actuating shaft, means rotatable with the dispensing means carrying shaft operative upon each revolution of said shaft to actuate the coupling means to disconnect the worm from the actuating shaft and releasably retain it in said position and means normally uncoupled from and adapted to be coupled with the actuating shaft by a coin upon rotation of the shaft to release the disconnecting means from and permit the coupling means to connect the actuating shaft with the worm.

3. In coin controlled vending apparatus, a rotatable shaft, revoluble merchandise dispensing means having an operative connection with the shaft and normally uncoupled therefrom, means normally urged to position to couple the shaft with the dispensing means, means rotatable with and about the axis of the dispensing means operative upon each revolution of said means to actuate the coupling means to uncoupling position to disconnect the dispensing means from the shaft and releasably retain it in said position, and means adapted to be coupled with and operative from the shaft by a deposited coin to release the coupling actuating means from and permit of movement of the coupling means to coupling position.

4. In coin controlled vending apparatus, revoluble merchandise dispensing means, a rotatable shaft, means to operatively connect and actuate the dispensing means from the shaft, means to couple said actuating means for the dispensing means with and uncouple the same from the shaft, means rotatable with the dispensing means operative upon each revolution thereof to actuate the coupling means to and retain it in uncoupling position, and means normally uncoupled from the shaft and adapted to be coupled with the shaft by a coin upon rotation of the shaft to release the coupling actuating means from and permit the coupling means to move to coupling position to connect the actuating shaft with the dispensing means.

5. In coin controlled vending apparatus, a rotatable shaft, an arm fixed to the shaft carrying and moving the merchandise dis-

pensing means through a circular path by the rotation of the shaft, an actuating shaft, means to actuate the dispensing means carrying shaft from the actuating shaft, means to releasably couple said actuating means with the actuating shaft and normally urged to coupling position, means rotatable with and operative upon each revolution of the dispensing means shaft to release said coupling means from the actuating means for the dispensing means carrying shaft and releasably retain it in said position, and means adapted to be coupled by a coin with and operative by the rotation of the actuating shaft to release the coupling means from its releasing means and couple the actuating shaft with the actuating means for the dispensing means carrying shaft.

6. A coin controlled vending apparatus as claimed in claim 5, wherein the dispensing means shaft actuating means and the means to couple the same with the actuating shaft comprises a worm wheel fixed to the dispensing means shaft, a worm loose on the actuating shaft arranged as a clutch member, and a clutch member rotatable with and slideable on the actuating shaft and normally urged into clutching relation with the worm.

7. In a coin controlled vending apparatus, a merchandise carrying casing having a coin chute, a rotatable shaft, an arm fixed to the shaft carrying and moving merchandise dispensing means through a circular path by the rotation of the shaft, an actuating shaft, a worm wheel on the first shaft, a worm loose on the actuating shaft meshing with the worm wheel and arranged as a clutch member, a clutch member rotatable with and slideable on the actuating shaft normally urged into clutching relation with the clutch member on the worm, a clutch shifter rotatable with and operative upon each revolution of the first shaft to actuate the clutch member out of clutching relation with the clutch member on the worm and releasably retain the clutch member in said position, and means operative from the actuating shaft and adapted to be coupled therewith by a coin deposited in the coin chute to actuate the clutch member to release the clutch shifter from and permit the clutch member to move into clutching relation with the clutch member on the worm.

8. A coin controlled vending apparatus as claimed in claim 7, wherein the clutch shifter rotatable with and operative upon each revolution of the dispensing means carrying shaft to actuate the clutch member out of clutching position with the worm, comprises a finger mounted on said shaft to rotate therewith and have a limited oscillatory movement about the shaft, and a spring to normally urge the finger to one of its extreme oscillatory positions, said finger being adapted to engage an annular flange on the clutch member and thereby held

against movement with the shaft against the tension of the spring and in conjunction with the spring move the clutch member to and releasably retain it in uncoupling position.

9. A coin controlled vending apparatus as claimed in claim 7, wherein the means operative from the actuating shaft and adapted to be coupled therewith by a coin to actuate the clutch member and release the clutch shifter therefrom to permit the clutching member to be moved into clutching relation with the worm, comprises a cam arm pivotally mounted at one end and engaging an annular flange on the clutch member and having a bifurcation in the free end, a pivoted lever having one end reduced and extended through the arm bifurcation and the shoulders at opposite sides of the reduced portion arranged as cam faces to engage the arm, a rock shaft extended transversely of the coin chute, a plate fixed to said shaft to have movement relative to a coin seat on the wall of the chute, an arm fixed to said rock shaft extending at an angle to the plate to position over the end of a lever opposite to its connection with the cam arm, and said lever being positioned by the clutch member when moved to clutching position to position the plate adjacent the chute wall and coin seat, and a finger on the actuating shaft adapted by the actuation of the shaft to have movement through an opening in the chute wall to engage a coin on the coin seat relative to the plate and through the impingement thereof on the coin by the rotation of the actuating shaft actuating the plate and thereby by the clutch member actuating arm to actuate the clutch to release the clutch shifter therefrom.

10. In coin controlled vending apparatus, a merchandise carrying casing having a coin chute, rotatable merchandise dispensing means, a rotatable actuating shaft, means to releasably couple the dispensing means with an actuate the same from the actuating shaft including clutch mechanism normally urged to clutching position, a clutch shifter rotatable with and operative upon each revolution of the dispensing means to actuate the clutch mechanism to unclutching position and releasably retain it in said position, a coin seat in the chute, a pivoted plate movable toward and away from the coin seat and normally positioned relative to the coin seat, a finger on the actuating shaft adapted by said rotation of the shaft to pass through a slot in the chute wall relative to the coin seat and through the coin move the plate away from the seat, and means actuated by said movement of the plate to release the clutch shifter from and permit the clutch mechanism to move to clutching position and connect the dispensing means with the shaft.

11. In a coin controlled vending apparatus as claimed in claim 10, a second plate pivotal-

- ly supported in the coin chute yieldingly urged into engagement with the chute wall and adapted to receive and support a coin deposited in the chute during the connection of the dispensing means with the shaft, and means connected to and rotatable with the support of the dispensing means operative to move said second plate to release and permit the coin supported thereby to drop to the coin seat.
- 10 12. In a coin controlled vending apparatus as claimed in claim 10, a second plate pivotally supported in the chute, a spring urging said plate into engagement with a chute wall to receive and support a coin deposited in the chute during the actuation of the dispensing means with the shaft, a cam arm secured to the pivot support of the plate and extended adjacent to the dispensing means, and an abutment rotatable with the dispensing means 15 adapted to engage the cam arm and move the plate against the action of its spring away from the chute wall to release and permit the coin to drop to the coin seat.
- 20
- 25 Signed in the city, county and State of New York, this 28th day of May, 1931.
